UNITED STATES PATENT OFFICE.

JOHN L. SKUTTLE, OF MASON CITY, IOWA.

AUTOMATIC WATER CONTROL FOR FURNACE AIR-MOISTENERS.

1,150,709.

Specification of Letters Patent. Patented Aug. 17, 1915.

Application filed October 3, 1914. Serial No. 864,856.

To all whom it may concern:

Be it known that I, JOHN L. SKUTTLE, a citizen of the United States, residing at Mason City, in the county of Cerro Gordo and State of Iowa, have invented certain new and useful Improvements in Automatic Water Control for Furnace Air-Moisteners, of which the following is a specification.

This invention relates to certain new and useful improvements in automatic water control for furnace air-moisteners.

The primary object of the invention is to provide an automatic filling valve for the evaporating pans of hot-air furnaces commonly known as air-moisteners, and whereby the water-inlet valve of the pan is automatically opened upon a lowering of the level of the liquid within the pan.

A further object is the provision of a cap of special form and adapted for pivotally mounting a float-member thereon while accommodating the valve operated by the float in its reciprocating movements as well as allowing for a removal of the valve and its stem without adjusting the cap.

A still further object is to provide a pipe section provided with a valve seat and positioned exteriorly of an evaporating pan, the said section coöperating with a cap secured thereto and positioned within the pan and adapted to mount both a float and valve member operatively thereon.

With these general objects in view and others that will appear as the nature of the invention is better understood, the same consists in the novel combination and arrangement of parts to be hereinafter more fully described, illustrated in the accompanying drawings, and set forth in the appended claims.

In the drawings forming a part of this application and in which like-designating characters refer to corresponding parts throughout the several views,

Figure 1 is a central longitudinal vertical sectional view through the evaporating pan of a furnace and through the invention installed thereon. Fig. 2 is an enlarged detail view partly broken away of the mounting bushing of the device and the members carried thereby. Fig. 3 is a perspective view of the valve and its stem detached, and Fig. 4 is a perspective view of the mounting cap.

Referring more in detail to the drawing,

it is to be understood that the present device is employed in connection with an evaporating pan 10 which constitutes an air moistener, being of the usual form provided in connection with hot-air furnaces for moistening the heated air which is generated by the furnace through the agency of fluid 11 such as water contained in the pan. The water supply pipe 12 is coupled to the pipe section 13 which in turn has the usual elbow 14 thereon.

The pan 10 has a perforation 15 through the wall thereof and through which perforation a sleeve 16 is screwed, the said sleeve being externally screw-threaded throughout its entire length and having a pipe section 17 engaging its outer end which pipe section has a threaded engagement with the said elbow 14. A cap 18 is threaded upon the sleeve interiorly of the pan while similar gaskets 19 encircle the sleeve 16 on the opposite sides of the pan wall and are forcibly engaged by the section 17 and cap 18 for forming an air and water tight connection.

A ball float 20 is provided within the pan partially immersed within the water contained therein and has a rod 21 secured thereto which is provided with a flattened head 22 having pivotal connection with a slotted post 23 upon the end wall 24 of the bushing, the said head being positioned through the slot 25 of the said post and mounted upon the removable bolt 26.

A valve stem 27 has a head 28 at one end provided with a longitudinal slot 29 which receives the rod head 22 and is connected thereto pivotally by means of another removable bolt 30. The end wall 24 of the cap has an eccentrically arranged opening 31 therein and through which the valve stem 27 extends, while a washer valve 32 of slightly less diameter than the diameter of the opening 31 is screwed upon the threaded free end 33 of the stem 27, being adjustably retained by means of the set-nut 34.

The manner of assembling the device will be apparent from the present description in that, with the bolt 26 removed, for disengaging the rod head from the bushing post the float and valve are disconnected therefrom although such parts are connected together. The sleeve is positioned through the pan perforation and the section 17 and the cap 18 are firmly screwed against the packings 19 and upon the sleeve 16, it being

noted that the cap is provided with opposite longitudinal ribs 35 adaptable as wrench hold surfaces.

The valve 32 has a tapered outer end 36 adapted to seat upon the tapered valve seat 37 within the pipe section 17. The valve is readily inserted through the opening 31 and the rod head then pivoted to the post 23 by inserting the bolt 26. It will thus be seen that the cap and pipe section 17 become substantially fixed members of the pan, and that for repairing the valve or the float members, a removal of the bolt 26 alone is requisite, it being noted also that the valve 32 is readily adjusted upon the valve stem and secured by means of the nut 34 as it becomes worn by constant contact with the valve seat.

While the forms of the invention herein shown are preferred, minor changes may be made therein without departing from the spirit and scope of the invention as claimed. A lowering of the level of the water within the pan results from evaporation and thereupon, the float 20 lowers with the water, which exerts a pull upon the valve 32 unseating the same from its seat 37 and allowing water to enter the pan until the normal level thereof is restored. An inflow of water to the pan is thus automatically effected upon evaporation, thus automatically maintaining a substantially normal water level in the pan.

What is claimed as new is:—

35. 1. A device of the class described comprising in combination with a pan having a perforation through the side thereof, a sleeve screw-threaded within said perforation, gaskets mounted upon said sleeve engaging the opposite faces of the pan side, a pipe section having a tapered inner portion and screw threaded upon the outer end of said sleeve in contact with the outer one of said gaskets, a cap screw threaded upon the inner end of said sleeve in contact with the interiorly positioned gasket, a float pivoted to said cap, and a valve pivotally connected

with said float for coöperating with said tapered inner portion.

2. A device of the class described comprising a pan having a perforation therethrough, an externally threaded sleeve threaded through said perforation, gaskets threaded upon said sleeve and engaging the opposite faces of the wall of the pan, a pipe section threaded upon the outer end of said sleeve in engagement with one of said gaskets, and having a tapered bore portion, a cap screw-threaded upon the inner end of said sleeve and having an end wall provided with an eccentrically arranged opening therethrough, oppositely positioned wrench-hold surfaces upon said cap, a post projecting from said end wall of the cap and eccentrically arranged thereon and provided with a longitudinal slot, a float within said pan, a rod secured to said float and having an enlarged flattened head positioned within said post-slot, a removable bolt connecting said post and head pivotally together, a valve stem pivoted to the said head and projecting through said cap opening and the said sleeve and into the said pipe section and a valve for coöperating with said tapered portion adjustably mounted upon said stem of less diameter than the diameter of said opening and a lock nut for said valve mounted upon said stem.

3. A float valve mounting cap of substantially tubular form comprising an end wall having an eccentrically positioned opening therethrough, diametrically positioned longitudinal wrench hold surfaces upon said cap, a post projecting from the said end wall and having a longitudinal slot in the free end thereof and eccentrically positioned on said end wall and provided with a pivot mounting in the longitudinal slot.

In testimony whereof I affix my signature in presence of two witnesses.

JOHN L. SKUTTLE.
